SIDNEY A. REEVE, OF STATEN ISLAND, NEW YORK

SWIMMING DEVICE

Application filed February 8, 1928. Serial No. 252,887.

My invention relates to swimming devices, usually made heavier than water, which are designed to facilitate the transmission of the swimmer's muscular powers to the water, for the better support and propulsion of his body through the water.

It has long been known that man's limbs are poorly adapted for the task of hydraulic propulsion. Hence, in addition to the various floatative devices which have been suggested for improving the buoyancy of the human body, a number of devices have been offered as improving the effectiveness of the human limbs as propellers. Since none of these earlier devices has met with wide success, it is proper to explain here, in order to define the novelty of this present invention, just why they have failed.

It is now common knowledge among nautical architects, although not yet familiar to the average layman, that devices for moving water are always heavily taxed by incidental surface-friction, eddies, etc., to such degree that none can succeed which do not minimize these losses with skill. Modern designers of ship-propellers are exhaustively technical in their efforts at the exclusion of every iota of wetted surface which does not earn its right to existence, by aiding in the acceleration of the water.

Earlier designers and inventors of swimmers' aids have not been properly alive to this necessity, nor sufficiently able in meeting it. Hence their failures. In contrast therewith this present improvement consists, in one of its essentials, in such an arrangement of parts that effort wasted in producing eddies or skin-friction shall have been so minimized as to make the device of real aid, rather than a hindrance, to the swimmer.

Another of its essentials lies in its utilization of the large extensor muscles of the upper leg and back, in contrast with previous efforts, which have utilized only the muscles below the knee; and also in its combination of the muscular powers of both arm and leg into a single useful result. Further essentials lie in its adaptability to the swimmer's continual need for maneuvering himself in the water. Also in its convenience for being cast

aside as he approaches the shore, or for being carried with him into the water as he enters. It is preferably made heavier than water, so as to be unobjectionable in swimming-contests, where any device at all buoyant would be ruled out because of that fact.

In the drawings of this specification:

Fig. 1 is a side-elevation of the swimmer in the water, with the device attached and in use.

Fig. 2 is an enlarged view of the part 11 of Fig. 1.

Fig. 3 is a cross-section of Fig. 2 along the line 3—3.

Fig. 4 is a modification of my invention in the direction of simplicity, useful for occasions less formal than those warranting the use of the complete invention.

In the drawings, B is a belt suitably attached about the swimmer's waist. Depending from this belt are four straps, cords or other flexible connections, namely: S, on the swimmer's left side, S' on his right side, and S2 and S3 passing down the front and then backwardly between the legs. Straps S and S2 join at P, behind the swimmer's left ankle, to support a pivot on which is fulcrumed the lever L. This lever has a cross-section relatively wide, as seen in Fig. 1, but thin in a direction normal to the paper of Fig. 1, as is visible in Fig. 3. Straps S' and S3 similarly combine to support a fulcrum behind the right ankle, on which is pivoted the lever L2.

The lever L carries a toe-piece T, preferably comprising some sort of a band over the toes whereby the retractor muscles of the leg may draw the lever up towards the swimmer's body. The lever L2 similarly carries a toe-piece T2. Each lever comprises a bend B' or B2 centered about the swimmer's respective heel. The lever L also has an extension L' beyond the fulcrum P, away from the swimmer. To the end of this extension is attached, by pin, the cord or light-rod C', perhaps tubular in form, which extends to the handle H' in the swimmer's left hand. The lever L2 is similarly provided with a connection leading to the swimmer's right hand. If the toe-pieces are provided with straps over the toes, these connections C' and C3 may

be flexible; but if there are no toe-straps then the connections C' and C3 must be capable of transmitting thrust, in order to bring the lever upwardly on its return-stroke, or to the 5 left as seen in Fig. 1. In any event, the straps S, S', S2 and S3 must be made sufficiently stiff so as not to flex under the resistance of the return, or idle, stroke.

Attached to the outer ends of the levers L, 10 L2 are pins 10, each forming a hinge for the two-part collapsible paddle 11, 11. Attached to the lower edge of the lever L, at 14, 14, are chains 12, 12 which, by their connection with the halves of the two-part paddle 15 at 13, 13, prevent the said halves from swinging open on hinge 10 too far; but preferably, for reasons stated below, these halves are thus permitted to swing slightly beyond a position at right-angles to the plane of motion of the 20 lever L, as seen in Fig. 3. When, on the back-stroke, these halves 11, 11 are brought together by the pressure of the water, they compress one or more light springs 15, whereby, when the working-stroke begins, they 25 are given a slight initial opening, so as to catch enough water to open them completely. Preferably the chains 12, 12 comprise elastic elements, such as the helical springs 16, 16 to minimize shock.

30 In the modification shown in Fig. 4, the sole advantage of which, over the device of Fig. 1, is simplicity, the connections with the swimmer's waist are omitted. The toe-piece T is enlarged into a shoe D, or other form which 35 can be held to the foot, while the pivot P becomes a mere bearing upon the instep. This arrangement loses that multiplication of the motion developed by the powerful extensor muscles of the upper leg and back which is a 40 prominent feature of my invention as shown in Fig. 1; but it permits the swimmer to walk into or out of the water without encumbrance to his hands, a feature to be appreciated in general beach-sports. The device of Fig. 4 45 may have an extension, as indicated in dotted lines, with hand-connection C.

In the device of Fig. 1 the swimmer carries one lever and handle in each hand, until 50 he has entered the water and has swum to sufficient depth for adjusting the apparatus as shown. He is then free to propel himself on his chest, on his side or on his back, at will. In all of these motions the dual strap-support 55 for the pivot P, which may be arranged differently from the exact way shown without departing from my invention, forms an important element in permitting him to develop lateral or torsional thrust upon the water. Also, during each working-stroke 60 the relative alinement of the parts 10, T and P as shown, with T to the right of a straight line joining 10 and P, together with the super-opening of the two-part paddle described above, together afford a stability of equilibrium of the lever in the water without which 65

the device would not be easily or effectively operable.

It is further essential to success that all the parts be kept to the greatest possible simplicity of form, so that their drag through the water may not eat up more power than is developed by the device; and this is especially true of the collapsible paddle, which moves through the water, when idle, at a velocity higher than any other part. It is 70 for this reason that this paddle is preferably kept to the two-part form, with its two halves fitting together, when closed, to form a clam-shell-like body approximating the true stream-line form. Such a form has a relatively blunt rounded nose, slightly convex sides, and a tapering tail.

I claim:

1. A swimming-device comprising a pair of levers, one for each foot, a collapsible paddle at one end of each lever, a hand-attachment at the opposite end of each lever, and a flexible attachment of each lever to the swimmer's body located between paddle and hand-attachment, substantially as described. 85

2. A swimming-device comprising a pair of levers, one for each foot, a collapsible paddle at one end of each lever, a hand-attachment at the opposite end of each lever, a flexible attachment of each lever to the swimmer's waist located between paddle and hand-attachment, and a toe-piece on each lever between said waist-connection and said paddle, substantially as described. 95

3. A swimming-device comprising a pivot 100 flexibly attached to the body of the swimmer, a unitary lever fulcrumed at the said pivot, a two-part collapsing paddle attached at the opposite end of the lever, and a toe-piece on said lever intermediate between fulcrum and paddle, the said paddle having an approximate streamline clamshell form when closed, substantially as described.

4. A swimming-device comprising two 110 levers, one for each foot, a fulcrum for each lever suspended from the swimmer's waist, a collapsing paddle at the end of each lever, and a toe-piece on each lever intermediate between fulcrum and paddle, the said paddles having an approximate streamline form when closed, substantially as described. 115

5. A swimming-device comprising a pivot 120 flexibly attached to the body of the swimmer, a unitary lever fulcrumed at the said pivot, a two-part collapsing paddle attached at the opposite end of the lever, and a toe-piece on said lever intermediate between fulcrum and paddle, the said paddle having elastic means 125 for opening it partially whenever the water-pressure permits, substantially as described.

6. A swimming device comprising a lever multiplying the motion of the swimmer's limbs, a collapsing paddle on said lever at the point of maximum multiplication hav- 130

- ing an approximate streamline form when closed, substantially as described.
7. A swimming-device comprising two levers, one for each foot, a fulcrum for each lever suspended from the swimmer's waist, a collapsing paddle located at the end of each lever, and a toe-piece on each lever intermediate between fulcrum and paddle, the said paddle having elastic means for opening it partially whenever the water-pressure permits, substantially as described.
8. A swimming-device comprising a lever for multiplying the motion of the foot, a collapsible paddle at the end of the lever having maximum motion, a hand-attachment at the opposite end of the lever, a bend in said lever in the plane of its motion intermediate between the foot-attachment and the hand-attachment, substantially as described.
9. A swimming-device comprising a pair of levers, one for each foot, a collapsible paddle at one end of each lever, a hand-attachment at the opposite end of each lever, an attachment of each lever to the swimmer's waist located between paddle and hand-attachment, a toe-piece on each lever between said waist-connection and said paddle, a bend in said lever in the plane of its motion intermediate between toe-piece and waist-attachment, and a reverse-bend in the same plane between the first mentioned bend and the hand-attachment, substantially as described.
10. In a swimming-device, a belt for the swimmer's waist, straps attached thereto at different points dually supporting a pivot located behind each heel or ankle, a lever fulcrumed on each such pivot and bent in the plane of its motion so as to extend below the corresponding foot and beyond its toe, a toe-piece on said lever, and a collapsing paddle on the end of said lever beyond the toe, substantially as described.
11. In a swimming-device, a belt for the swimmer's waist, straps attached thereto at different points dually supporting a pivot located behind each heel or ankle, a lever fulcrumed on each such pivot and bent in the plane of its motion so as to extend below the corresponding foot and beyond its toe, a second extension of said lever from the pivot in a direction away from the swimmer's foot, a toe-piece on the first mentioned extension, a connection of the second mentioned extension to the swimmer's hand, and a collapsing paddle on the end of the first mentioned extension, beyond the swimmer's toe, substantially as described.
12. In a swimming-device, a lever attached to the swimmer's toe and extending substantially in the plane of the bent leg, a collapsible paddle on the end of said lever beyond the toe, a bearing of said lever on the swimmer's instep, and an extension of said lever backwards beyond the heel, carrying at its end a connection with the swimmer's hand, substantially as described.
13. In a swimming-device, a lever suspended from the swimmer's body multiplying the motion of his limbs, a collapsible paddle attached to the lever at the point of maximum multiplication, having elastic means for reducing shock at the end of both opening and closing movements, substantially as described.
14. A swimming-device comprising a lever fulcrumed near the swimmer's foot at the end of a support flexibly attached to the swimmer's body, a collapsing paddle attached at the opposite end of the lever, and a toe-piece on said lever intermediate between fulcrum and paddle, substantially as described.
15. A swimming-device comprising two levers, one for each foot, for each lever a fulcrum near the swimmer's foot supported from near the swimmer's waist, and a toe-piece on each lever intermediate between fulcrum and paddle, substantially as described.
16. A swimming-device comprising two levers, one for each foot, a fulcrum near the swimmer's foot for each lever, each fulcrum being supported from two or more points near the swimmer's waist, a collapsing paddle at the end of each lever, and a toe-piece on each lever intermediate between fulcrum and paddle, substantially as described.
17. A swimming-device comprising a pair of levers, one for each foot, each lever fulcrumed near the foot on supports flexibly attached near the swimmer's waist, a collapsible paddle at the end of each lever, a toe-piece on each lever intermediate between fulcrum and paddle, and a bend in each lever in the plane of its motion such as to bring the toe-piece below a straight line connecting the paddle with the fulcrum, the word "below" being understood in the sense of the swimmer's altitude, substantially as described.
18. A swimming-device comprising a unitary lever fulcrumed on a support flexibly attached near the swimmer's waist, carrying at its outer end a collapsible paddle, with an intermediate point on said lever responsive to the magnitude and direction of motion of the swimmer's toe, substantially as described.
19. In a swimming-device heavier than water, a lever multiplying the extensor motion of the knee-joint and the flexor motion of the elbow, having at its point of maximum multiplication a collapsible paddle, substantially as described.
20. A swimming-device comprising a lever multiplying the motion of the swimmer's limbs, a completely collapsible paddle on said lever at the point of maximum multiplication, said paddle comprising two halves forming when closed a hollow clam-shell body of substantially stream-line shape, and having elastic means for opening it partially

whenever the water-pressure permits, substantially as described.

21. A swimming-device comprising a lever multiplying the motion of the swimmer's limbs, a two-part completely collapsing paddle on said lever at the point of maximum multiplication, the two halves of said paddle forming, when closed, a hollow clam-shell body of substantially stream-line shape, and being arranged to rotate, when open, into positions beyond the plane through the hinge normal to the plane of the lever's motion, the axis of which hinge passes, when prolonged, below the fulcrum of the multiplying lever, relatively to a vertical position of the swimmer's body, substantially as described.

22. A swimming-device comprising a unitary lever fulcrumed upon a support from the swimmer's body and multiplying the magnitude of motion of a limb, which supporting fulcrum is arranged to resist both vertical and lateral displacement, and a collapsible paddle attached to said lever at its point of maximum multiplication of motion, the two halves of said paddle forming, when closed, a hollow clam-shell body of substantially stream-line shape, substantially as described.

23. In a swimming-device heavier than water, a lever multiplying the extensor motion of the knee-joint, having at its point of maximum multiplication a collapsible paddle, the two halves of said paddle forming, when closed, a hollow clam-shell body of substantially stream-line form, substantially as described.
